EDGAR MAJOR WINFREY, OF WICHITA FALLS, TEXAS.

DOORCHECK.

Application filed August 19, 1925. Serial No. 51,224.

My invention relates to improvements in door checks, and it consists in the combinations, constructions and arrangements herein described and claimed.

- 5 An object of the invention is the provision of a simple, reliable and highly efficient door check which will afford facilities for checking the swinging movement of a door to which it has been applied so that the door
 10 will remain in a position to which it has been swung and will be prevented from swinging rapidly from open to closed position or vice versa, thus precluding slamming of the door either to closed or fully open position.
 15 A further object of the invention is the provision of a door check of the character described which will take up but little space, will be inconspicuous and will not offer any obstruction to passage through the doorway.
 20 Other objects and advantages of the invention will be apparent from the following description, considered in conjunction with the accompanying drawings, in which—

Figure 1 is a fragmentary perspective view showing a practical embodiment of the invention operatively applied to a door and frame construction.

Figure 2 is a longitudinal vertical section through the door check.

Figure 3 is a relatively enlarged vertical section through an adjusting screw of the door check, showing in side elevation a member for turning the adjusting screw.

Figure 4 is a perspective group view of certain parts of the door check separated from each other.

Figure 5 is a perspective view of an attaching member which is comprised in the door check.

Figure 6 is a view similar to Figure 1, showing a second form of door check embodying the same invention.

Figure 7 is a fragmentary vertical section through the second form of door check.

Figure 8 is a perspective group view of certain elements of the second form of door check disassembled.

Figure 9 is a perspective view of a friction sleeve and attaching arm which are used in each of the two forms of the invention which are illustrated in the drawings.

In Figure 1, I show a door 1 which is at-

tached to a frame 2 by means of a hinge which is of the loose-pin type of construction and which comprises a pair of cooperative hinge plates or leaves 3 and 4 respectively, having alined sleeve portions 3^a and 4^a respectively at their adjacent edges through which a pin may extend. The hinge leaf 3 is attached by screws 5 to an edge of the door 1, while the hinge leaf 4 is attached by screws 6 to the frame 2.

In carrying out the invention, I replace the usual pin for connecting the leaves 3 and 4 by a pin 7 which extends through the alined sleeve portions 3^a and 4^a of the hinge leaves and is enlarged adjacent to its upper end and above the upper sleeve portion of the hinge to provide a frusto-conical or upwardly tapering head portion 8 which is merged at its lower end into a neck portion 9 and which terminates at its upper end in a reduced portion 10. The neck portion 9 is non-circular in cross sectional contour and is adapted to fit in an opening 11 in an end portion of an arm 12, the lower end portion of the pin being projected through the opening 11 before the pin is inserted in the alined sleeve portions of the hinge sleeves. The arm 12 is twisted intermediate its length so that the inner end portion thereof will fit snugly between the lower end of the head 8 and the upper end of the adjacent sleeve portion of the hinge while the outer end portion of the arm will lie in the plane of one of the hinge leaves, as for example in the plane of the hinge leaf 4 as shown in Figures 1 and 2.

The outwardly tapering or frusto-conical head 8 constitutes an inner friction member on which a tapering tubular outer friction sleeve 13 is disposed, the outer friction sleeve being spaced from the inner friction member by an intermediate friction member 14 which is a lining or layer of leather or like compressible material. An arm 15 is rigid with the friction sleeve 13 and extends radially outward therefrom substantially in the plane of the hinge leaf 3 and of course at the upper end of the latter. The outer end portion of the arm 12 is provided with apertures 16 for the reception of screws 17 for securing the outer end portion of the arm 12 to the frame 2 as shown in Figure 1, while

the arm 15 is apertured as at 18 for the reception of screws 19 for securing the arm 15 to the adjacent edge of the door 1.

A pressure transmitting washer 20 is slideable on the reduced upper end portion 10 of the pin and is held against turning on the reduced upper end portion 10 of the pin by reason of the engagement of a projection 21 which extends inwardly from the inner wall of the washer 20 with a flattened portion 22 on the periphery of the reduced upper end portion 10. A pressure adjusting screw 23 has a shank adapted for threaded engagement with an internally threaded axial socket 24 which extends in the pin through the reduced upper end portion 10 and into the head 8. The pressure adjusting screw has a head indicated at 24 which is adapted, when the screw is tightened, to contact with the washer 20 and to transmit motion through the latter to the outer friction sleeve 13, thereby tending to force the friction sleeve 13 downwardly and thus increasing the friction between the concentric friction members 13, 14 and 8.

It is manifest that this friction will tend to check the swinging movement of the door since the inner friction member is held against turning relatively to the axis of the pin 7 while the outer friction member is permitted to turn under stress about the axis of the pin but the turning movement of the outer friction member is yieldingly resisted because of the friction between the associated friction members. This resistance, of course, can be increased within limits by tightening the adjusting screw 23. In other words, the inner friction member is held substantially rigid with one of the hinge leaves while the outer friction member is secured to the same member as the other hinge leaf and therefore swinging movement of the hinge leaves towards or away from each other will be attended by friction which will check such swinging movement.

The head 24 of the adjusting screw 23 may be castellated and the adjusting screw may support a member for turning the screw, this member being shown as a rod comprising a lower section 25 and an upper section 26 hinged to each other at their adjacent ends and being slideable in a bore 27 which extends axially of the adjusting screw, the lower section 25 having a head 55 at 28 at its lower end for engaging with a stop 29 to limit the axial movement of the rod 26-25 upward in the bore of the adjusting screw. The length of the lower section 25 of the screw-operating rod is approximately the same as the distance from the stop 29 to the plane of the upper face of the head of the screw, whereby the upper section of the screw-operating rod can be swung laterally to position to extend in 65 any one of the radial grooves 30 in the up-

per side of the head of the screw when the screw-operating rod is in raised position, and a relatively great leverage then can be obtained for turning the screw by manipulating the upper section of the rod in the 70 manner of a handle, the upper section of the rod being formed with a knob 31 at its upper end so that it can be firmly grasped and conveniently manipulated.

From the foregoing description of the various parts of the device, the operation thereof may be readily understood. The device when applied to a door and frame construction takes up but very little space, does not detract from the appearance of the door or tend to obstruct passage through the doorway. The intermediate friction member 14 is the only member of the device upon which any appreciable wear will take place and this member can be replaced when required 85 quickly and easily and at slight cost. Since the intermediate friction member 14 is made of leather, it is obvious that the functioning of the device will be attended by but very little, if any, noise.

In the form of the device exhibited in Figures 6 and 7, the hinge leaf 4 of the preferred form of the device is replaced by a hinge leaf designated 32 which differs from the hinge leaf 4 only in that it has a notch or notches at 33 in its upper sleeve portion, indicated at 32^a, at the inner edge thereof and through which the pin for connecting the hinge leaf 32 to the hinge leaf 3 extends. This pin is designated 7 as 95 in the preferred form of the device and the non-circular neck portion 9 of the pin engages with the notch or notches 33 to prevent turning of the pin 7 about its axis relatively to the axial line of the sleeve portions 32^a of the hinge leaf 32, whereby the pin 7, including the head portion 8 thereof, is substantially rigid with the hinge leaf 32. The attaching arm 12 of the preferred form of the device therefore is omitted from the second form of the device. The remaining elements of the second form of the device are identical with corresponding elements of the preferred form of the device and therefore will not be described herein, the same reference numerals having been used to indicate like parts of the two forms of the device throughout the several views of the drawings.

The operation of the modified or second form of the device is identical in essential respects with the operation of the preferred form of the device.

Obviously, the invention is susceptible of embodiment in forms other than those which are illustrated in the accompanying drawings, and I therefore consider as my own all such modifications and adaptations thereof as fairly fall within the scope of the appended claims.

What I claim is:

1. A door check comprising the combination with a hinge having a pair of cooperative hinge plates formed with aligned sleeve portions at their adjacent edges and a pin extending through said aligned sleeve portions, of a frusto-conical friction member, a non-circular neck portion merging said frusto-conical friction member and said pin one into the other, an arm having an opening through which said non-circular neck portion extends and with which the non-circular neck portion is engaged, said arm being adapted for attachment to the same member as one of said hinge plates, a tapering friction sleeve overlapping said first named friction member, said friction sleeve having an outwardly extending arm adapted to be attached to the same member as the second of said hinge plates, said first named friction member having a reduced upper end portion, a pressure transmitting washer slideable on said reduced upper end portion and held against turning on the latter, and means adjustably engageable with said upper end portion for forcing said pressure transmitting washer against the upper end of said friction sleeve to hold said friction sleeve in frictional association with said first named friction member. 95

2. A door check comprising the combination with a hinge having a pair of cooperative hinge plates formed with aligned sleeve portions at their adjacent edges and a pin extending through said aligned sleeve portions, of a frusto-conical friction member, a non-circular neck portion merging said frusto-conical friction member and said pin one into the other, an arm having an opening through which said non-circular neck portion extends and with which the non-circular neck portion is engaged, said arm being adapted for attachment to the same member as one of said hinge plates, a tapering friction sleeve overlapping said first named friction member, said friction sleeve having an outwardly extending arm adapted to be attached to the same member as the second of said hinge plates, said first named friction member having a reduced upper end portion, a pressure transmitting washer slideable on said reduced upper end portion and held against turning on the latter, and an adjusting screw engaged with a threaded socket in said reduced upper end portion and having a head bearing against said pressure transmitting washer. 115

3. A door check comprising the combination with a hinge having a pair of cooperative hinge plates formed with aligned sleeve portions at their adjacent edges and a pin extending through said aligned sleeve portions, of a frusto-conical friction member, a non-circular neck portion merging said frusto-conical friction member and said pin

one into the other, an arm having an opening through which said non-circular neck portion extends and with which the non-circular neck portion is engaged, said arm being adapted for attachment to the same member as one of said hinge plates, a tapering friction sleeve overlapping said first named friction member, said friction sleeve having an outwardly extending arm adapted to be attached to the same member as the second of said hinge plates, said first named friction member having a reduced upper end portion, a pressure transmitting washer slideable on said reduced upper end portion and held against turning on the latter, an adjusting screw engaged with a threaded socket in said reduced upper end portion and having a head bearing against said pressure transmitting washer, and a screw operating member comprising a rod slideable in an axial bore in the screw, said rod comprising a pair of hinged-together sections, and said screw having an integrally extending stop for limiting the upward movement of said rod, the head of said screw having radial slots in its upper face, whereby the upper section of said rod can be swung downwardly when the rod is raised to position to extend through one of said radial slots to provide a handle for turning said screw. 95

4. A device of the character described comprising the combination with a pair of hinged plates having aligned sleeve portions at their adjacent edges and a pin extending through said aligned sleeve portions, said pin extending above the plane of the upper ends of said hinge plates and being enlarged adjacent to its upper end to provide a frusto-conical friction head, said pin having a neck portion of non-circular contour below said head and having a reduced upper end portion above said head, a tapering tubular friction sleeve overlapping said friction head, a compressible friction lining between said sleeve and said friction head, means engageable with said non-circular neck portion and attachable to the same member as one of said hinge plates to hold said pin against turning relatively to said one hinge plate, means carried by the reduced upper end portion of the pin for adjusting the position of said friction sleeve on said friction head, and an attaching arm extending outwardly from said friction sleeve and adapted for attachment to the same member as the second of said hinge plates. 120

5. A device of the character described comprising the combination with a pin having a pair of hinge plates formed with aligned sleeve portions at their adjacent edges, the upper of said sleeve portions having a notch in its upper end, a pin extending through said sleeve portions and having a neck portion engaged with said notch to hold said pin against turning relatively to 130

one of said hinge plates, said pin having a frusto-conical head portion above said neck portion, a tapering conical friction sleeve overlapping said frusto-conical head portion, said sleeve having a laterally extending arm adapted for attachment to the same member as the second of said hinge plates,

and means for adjusting the position of said friction sleeve on said friction head to vary the friction which will be created when said hinge plates move relatively to each other about the axis of said pin. ¹⁰
